UNITED STATES PATENT OFFICE.

MANUEL HUITRON NERI, OF LOS ANGELES, CALIFORNIA.

DEVICE FOR SPRAYING HOT FLUID SUBSTANCES.

Application filed April 4, 1921. Serial No. 458,391.

To all whom it may concern:

Be it known that I, MANUEL HUITRON NERI, a citizen of the United States, and resident of Los Angeles, in the county of 5 Los Angeles and State of California, have invented certain new and useful Improvements in Devices for Spraying Hot Fluid Substances, of which the following is a specification.

10 This invention relates to devices for spraying hot fluid substances, having reference particularly to an electrically heated and operated apparatus for spraying hot tar in the process of enameling.

15 The invention has for its objects the provision of means for electrically heating, conducting, pumping and spraying hot tar, comprising an assemblage of simply constructed elements arranged in readily operable and novel correlation in such manner as to maintain an even temperature and obviate cooling of the fluid while it flows through the apparatus.

20 The above named and other objects are attained by employing an electric motor, an electrically heated duplex pump operable by said motor, electrically heated means for feeding fluid to said pump, electrically heated means for conducting and discharging fluid from said pump, means for controlling the electric motor, and means for encasing, assembling and mounting the parts, and other novel features, all as hereinafter fully described and specifically set forth in the appended claims.

25 In the accompanying drawings forming part of this specification, Figure 1 is a side elevation illustrating an embodiment of my improvements, parts thereof being shown in sectional elevation;

30 Fig. 2 a vertical sectional view taken on the line 2—2 of Fig. 1;

35 Fig. 3 is a sectional plan view taken on the line 3—3 of Fig. 2; and Fig. 4 is a longitudinal sectional view of a fragment of tubing adapted to be employed in the apparatus assemblage.

40 In the drawings 1 indicates an electric motor of any adaptable construction and capacity; to the shaft of said motor is connected a bevel pinion 2 which meshes with a bevel wheel 3, mounted on a transverse horizontal shaft 4 which is journaled

through standards 5 fixed on the upper wall 6, of a housing 7, said housing also supporting a fixed bracket 8 which carries the motor 1.

45 The shaft 4 carries on one end a wheel 9, having a crank-pin 10 which is in pivotal connection with a connecting rod 11, said rod engages at its lower end a reciprocating piston 12 of a cylinder 13, said cylinder is open at the top and closed at the bottom and is supported by the lower wall of the housing 7. On the other end of the shaft 4 is a wheel 9^a, having a crank-pin 10^a, which is in pivotal engagement with a connecting rod 11^a, which engages a reciprocating piston 12^a, of a cylinder 13^a, said cylinder also being closed at the bottom and 50 open at the top.

55 Each of the cylinders is provided with an inlet opening 14, having seated therein a conical valve 15, said valve having a stem 16 which reciprocates through a fixed spider 17, a head 18 being formed on the lower end of the valve stem which supports a normally expanded spiral spring 19, adapted for maintaining the valve 15 normally closed. Laterally connecting the cylinders 13 and 13^a, is casing 20 having at one end an opening 21 which communicates with an outlet port 22 of the cylinder 13, the opposite end of said casing having an opening 21^a, which communicates with an outlet port 22^a of the cylinder 13^a, these openings of the casing are ground for seating valves 23 and 23^a which are mounted on a common stem 24 which reciprocates through a fixed bearing 25, whereby said valves may be 60 alternately opened and closed, as herein-after described.

65 Leading upwardly from the valve casing 20 is a tubular outlet 26 which connects with an elbow 27, said elbow being coupled to a lateral tube 28 which extends through the housing 7 and is coupled to a reinforced flexible tube 29, which is connected, by means of a coupling 30, with a branch 31 of an ejector comprising said branch 31 and an obliquely extended nozzle member 32 having a contracted outlet 33. As a means for controlling the flow of fluid through the outlet 33, whereby it may be atomized, I provide a needle valve 34 having a screw-threaded outer end part 35

which is threaded through a stud 32^a, of the branch 32 and is adapted to be turned by means of a knob 35^a, whereby the needle valve may be longitudinally adjusted to control the flow of fluid through the outlet 33.

Surrounding the ejector is a sheet metal housing 36 having in its lower end an asbestos plug 37 through which extends resilient contact plates 38 and 39 which are adapted to be contacted by a spring-pressed push button 40, composed of insulating material, the plates 38 and 39 being normally out of contact. These plates are electrically connected with the two conductors 41 and 42 which are in an electrical circuit in connection with the motor 1, whereby the circuit may be alternately opened and closed by manipulating the push button 40. The wire conductors 41 and 42 are encased in an ordinary insulator tube 43 mounted on the flexible tube 29, by means of a collar 44, only a short section of tube 43 being shown, and the means for connecting the conductors with the motor are not shown, as I use any well known adaptable means now in common use. To the housing 36 is connected a handle 36^a, whereby the ejector may be moved over a surface to be coated.

As a means for feeding fluid substance to the cylinders 13 and 13^a, I employ a vertical tube 45, having a branch 46 which leads into the cylinder 13, and a branch 47 which leads into the cylinder 13^a; this tube 45 and its branches are encased within a mica coating 48, around which is coiled a high resistance conductor 49 which is covered by means of a mica coating 50, whereby the conductor 50 is effectually insulated, a metal casing 51 being employed as a means for protecting the mica and maintaining the parts in rigid connection.

Fixed to the lower end of the housing 7 by means of bolts 52 and nuts 53, is a cylindrical screen 54 having heads 55 and 56, thus providing means for screening the molten tar and preventing foreign substances from being drawn into the apparatus.

The cylinders 13 and 13^a, are also surrounded by means of a high resistance conductor 57 and mica insulators 58 and 59; and a similar high resistance conductor 60 is coiled around the two branches of the ejector for maintaining said ejector heated when the device is in use, said conductor being insulated by means of mica coatings 61 and 62, as shown in Fig. 1 of the drawings wherein only parts of the heating element and its insulators are shown, but in practice the entire ejector is covered. A heating element may also be incorporated in the structure of the flexible tube 29, if desirable, as indicated by 29^a Fig. 4 of the drawings.

In practice the several heating elements are interposed in an electrical circuit either

in connection with the motor 1 or any other source of supply of sufficient capacity to energize them.

The bracket 8 for carrying the motor 1, is provided with an extension 8^a; through which is threaded a screw 63 having a spherical end 64 which is swiveled to a clamp 65 for engagement with a tank, as 66, Fig. 1 of the drawings, for containing a supply of hot molten tar for feeding the apparatus.

Pivoted to the extension 8^a, of the bracket 8, is an extensible and contractible leg 67, which is connected by means of a screw 68 and a thumb nut 69, said leg comprising two slidale members 70 and 71, adapted to be locked by means of a thumb screw 72, whereby the leg may be maintained at any desired length for contact with a surface upon which the tank 66 is placed, for the purpose of stabilizing the structure and maintaining it in rigid condition when in use.

In the operation and use of the invention, the apparatus is clamped to a tank 66 containing a quantity of hot molten tar, the lower edge of the screen 54 resting on the bottom of the tank, whereby the tar may seep through the walls of the screen and enter the lower or inlet end of the tube 45, current is then switched on by pushing the button 40 and contacting the plates 38 and 39, whereupon reciprocating movement is transmitted to the pistons 12 and 12^a, by means of the motor 1, and the heating elements constituting the high resistance coils are electrically heated to maintain the high temperature of the tar while it passes through the apparatus, the tar being drawn into the cylinders through the valves 15 on the upward strokes of the pistons and forced alternately through the valves 21 and 21^a into the outlet tube 26, and thence to the flexible tube 29 and the ejector on the downward strokes, whereby a constant flow of hot tar is ejected through the aperture 33 of the nozzle and atomized by means of the needle valve 34, to evenly spread it on the surface being coated or enameled, the ejector being manipulated by means of its handle 36^a.

When the apparatus is not in use, or immediately after and before its use it should be electrically heated and thoroughly cleaned by pumping air therethrough, and the flexible tube 29 should be thoroughly heated before attempting to bend it.

I do not wish to be understood as limiting myself to the employment of the specific details of mere mechanical construction of the elements of my improvements as herein shown and described, as I believe that under the spirit of my invention and scope of the appended claims I am entitled to employ slight variations of mechanical construction.

Having thus described my invention, what I claim as new and desire to secure by Letters Patent, is:

1. An apparatus for enameling surfaces with hot tar, comprising an electric motor, a pump, means for transmitting power to said pump and means for electrically heating it, and means for conducting hot tar from said pump, and means for electrically heating said conducting means.
2. An apparatus for enameling surfaces with hot tar, comprising an electric motor, a duplex pump, means for transmitting power to said pump, and means for electrically heating, housing and screening said pump.
3. An apparatus for enameling surfaces with hot tar, comprising an electric motor, a duplex pump constituting two cylinders, reciprocating pistons and a two-branched inlet tube, feed valves for said cylinders, and valve means laterally connecting them, and high resistance conductors surrounding said cylinders and said inlet tube, an ejector and means connecting it with the outlets of the cylinders, and means for electrically heating said ejector.
4. An apparatus for enameling surfaces with hot molten substances, comprising an electric motor, a duplex pump, means for transmitting power to said pump, and means for housing and electrically heating said pump, and feeding means for said pump and means for electrically heating the same, and means connected with said pump for conducting and ejecting hot fluid substance, and means for electrically heating said conducting and ejecting means.
5. An apparatus for enameling surfaces with hot molten substances, comprising an electric motor, a duplex pump, means for electrically heating said pump, means for transmitting power from said motor to said pump, and valved feeding means for said pump, and means for electrically heating said feeding means, and means connected with said pump for conducting and ejecting the hot fluid substance, and means for electrically heating said conducting and ejecting means.
6. An apparatus for enameling surfaces with hot molten substances, comprising an electric motor, a duplex pump, means for transmitting power from said motor to said pump, and valved feeding means for said pump, and means for electrically heating said feeding means, and means for housing and electrically heating said pump, and means for supporting said motor on said housing means and means for fastening the apparatus to a container, and adjustable supporting means for stabilizing the device.
7. An apparatus for enameling surfaces with hot molten substances, comprising an electric motor, a duplex pump, means for transmitting power from said motor to said pump, and valved feeding means for said pump, and means for electrically heating said feeding means, and means for housing said pump and means for electrically heating the same, and means for supporting said motor on said housing means, and an ejector, and means for conducting the hot substance from the pump to said ejector, and means for electrically heating said ejector, means for controlling the motor.
8. In an apparatus for enameling surfaces with hot molten substances, an electric motor, control means for said motor, a pump, power transmission means for operating said pump, feed means for said pump, means for electrically heating said pump and feed means, and means for conducting the hot molten substance from said pump, and ejector means connected with said conducting means, and means for electrically heating said ejector means, and means for controlling the supply of current for the heating means.

Signed at Los Angeles, in the county of Los Angeles, and State of California, this twenty-ninth day of April, 1922, A. D.

MANUEL HUITRON NERI
